(57) **CLAIM**

We claim the ornamental design for a stent, as shown and described.

DESCRIPTION

FIG. 1 is a perspective view of a stent showing our new design;
FIG. 2 is a bottom perspective view thereof;

FIG. 3 is a front view thereof;

FIG. 4 is a left side view thereof;

FIG. 5 is a right side view thereof;

FIG. 6 is a top view thereof;

FIG. 7 is a bottom view thereof.

FIG. 8 is a perspective view of second embodiment of a stent with stiches;
FIG. 9 is a bottom perspective view thereof;

FIG. 10 is a front view thereof;

FIG. 11 is a left side view thereof;

FIG. 12 is a right side view thereof;

FIG. 13 is a top view thereof; and,

FIG. 14 is a bottom view thereof.
